BOX

Samuel Reich, Brooklyn, N. Y.

Application April 13, 1934, Serial No. 720,346

1 Claim. (Cl. 229—31)

This invention relates to improvements in paper boxes in general and more particularly to boxes of the dish or tray type.

The primary object of the invention resides in a paper box of the type commonly used by delicatessen and grocery stores in the sale of loose pickles, sauerkraut, lard, and other like food-stuffs, which is constructed of a single blank of material folded in a novel manner to provide a continuous bottom and side wall structure to avoid corner joints, and thus overcome the danger of leakage of the moisture contents of the box.

Another object of the invention is to provide a folding tray box which when unfolded assumes a flat position to enable compact stacking for shipping and storage purposes, and which may be readily folded into a set-up position when needed for use.

A further object is the provision of a folding tray box in which the upstanding walls thereof are joined by foldable webs, which fold outwardly and flat against adjacent walls, the folded webs being held flat by flaps bent down from the top edges of the walls to avoid accidental unfolding of the same.

A still further object is to provide a cardboard tray box in which the corners are so constructed as to render them watertight and which construction reinforces the box to strengthen the same.

With these and other objects in view, the invention resides in the certain novel construction, combination and arrangement of parts, the essential features of which are hereinafter fully described in the following specification, are particularly pointed out in the appended claims, and are illustrated in the accompanying drawing, in which:

Figure 1 is a plan view of the blank from which my folding box is constructed.

Figure 2 is a perspective view of the box in set-up position for use.

Figure 3 is an enlarged detail horizontal sectional view through one end of the box.

Figure 4 is a vertical sectional view on the line 4—4 of Figure 2.

Figure 5 is a fragmentary perspective view illustrating the manner in which corner webs are folded.

Figure 6 is a perspective view of a modified form of box.

Figure 7 is a perspective view of a further modification.

Referring to the drawing by reference characters, the letter A designates the cardboard blank 55 of material from which my folding box is con-

structed and which blank is of substantial rectangular configuration in plan as seen by reference to Figure 1 of the drawing. The blank A is scored lengthwise on the parallel score lines 10 and 11 and transversely on the lines 12 and 13, the longitudinal and transverse score lines joining each other and defining a bottom wall 14. The blank beyond the longitudinal score lines 10 and 11 is further scored on the lines 15—15 to define side walls 16—16 and flaps 17—17 which extend 10 the length of the side walls 16. The blank is also scored transversely beyond the score lines 12 and 13 as at 18 to define side walls 19—19 and flaps 20—20. In order to distinguish the shorter side walls 19—19 from the longitudinal side walls 15—16, I shall refer to the walls 19 as end walls which in actual practice when the box is in set-up position constitute side walls and coact with the walls 16 to provide a continuous side wall structure.

Connecting the adjacent ends of the side walls 16 and end walls 19, are triangular shaped corner webs 21, the same being formed by scoring the blank on the inwardly converging lines 22—22, the inner meeting ends of the score lines 22 terminating at the respective corners of the bottom wall 14 whereas the outer diverging ends of the lines 22 meet the ends of the respective fold lines 15 and 18. The webs 21 are divided into two folds by a score line 23, the said lines 23 extending 30 from the apex portions of the triangular shaped webs to the outer free edge of the webs and which lines divide the webs into two identical outwardly foldable sections. The score lines 22 extend at an obtuse angle from the bottom fold lines 10, 11, 12, 35 and 13 so that when the box is in a set-up position in a manner to be presently explained, the side walls extend upwardly and outwardly as best seen in Figure 4 of the drawing.

In order to set up the box from the blank shown in Figure 1, the triangular shaped corner webs 21 are folded outwardly on the score lines 23 while the flaps 17 and 20 are folded downwardly against the exterior side walls 16 and 19 respectively as best illustrated in Figure 5 of the drawing. The outward folding of the webs 21 tends to fold the side and end walls inwardly to shape the body of the box, after which the two folds or sections of the webs 21 are folded flat against each other and the two folds of the webs are then 50 folded flat against one of the adjacent side walls of the body structure. The central portion of the flaps 17 and 20 are adhesively secured to the respective side walls of the box as at 24 so as to leave the ends of the flaps free. The folded corner 55

webs 21 pass beneath the free ends of the flaps 17 and 20 so that the flaps overlie the folded corner webs and prevent accidental unfolding of the same when the box is in a set-up position. 5 Although I have mentioned that the flaps 17 and 20 are adhesively secured to the respective side walls, it will be understood that the same may be stitched or otherwise secured, and this fastening of the flaps to the side walls is performed by the 10 manufacturer so that when the boxes are sold for use, it is only necessary for the user to fold the corner webs in the manner above described. In such case, the box may be folded to the flat position shown in Figure 1 and will appear identical 15 to the showing in this figure with the exception that the flaps 17 and 20 are folded upon the respective side walls 16 and 19. When the box is in a flat unfolded position, the same may be compactly stacked for storage and shipping 20 purposes, or if it is desired, the storekeeper may set up a supply of boxes and nest them one within the other for use as needed.

In Figure 6 of the drawings, the construction is substantially the same as that shown in the 25 preceding form, with the exception that the corner folds 25 are folded over the end wall of the box body, while only the end walls are provided with holding flaps 26, which have their opposite ends overlapping the corner flaps 25 and 30 which ends are adhesively secured to the said corner flaps. The portions of the flaps 26 intermediate the corner folds 25 are free of the adjacent side walls.

In Figure 7 of the drawing, a further modification 35 has been shown wherein the bottom of the box body is provided with depending legs 27 struck out from the box bottom and being disposed co-extensive with the side walls. Also in this modification, the ends of the holding flaps 28 are ex-

tended beyond the ends of the side walls as at 29 and adhesively secured to the longitudinal side walls. The flaps 28 of course overlie the corner folds 30 to hold the box in a set-up position. In the form of boxes shown in Figures 6 and 7, it is 5 necessary to nest them one within the other as they cannot be folded flat as in the preferred form without breaking the adhesive bond which secures the holding flaps to the side walls of the box body. 10

The form of the box shown in Figure 7 will be found useful for the packing of berries wherein ventilation within the box from beneath is desirable.

While I have shown and described what I deem 15 to be the most practical embodiments of my invention, I wish it to be understood that such changes as come within the scope of the appended claim, may be resorted to if desired.

Having thus described the invention, what I 20 claim is:—

A box constructed entirely from a single blank of cardboard comprising a tray-like body of rectangular configuration having a bottom wall, upstanding opposed end walls, and upstanding 25 opposed side walls, down-turned flaps integral with and extending the width of the opposed end walls and disposed exteriorly of said end walls, triangular shaped corner webs integral with adjacent side and end walls, each of said corner webs being folded outwardly upon itself and thence inwardly flat against the outside of said end walls, the top portions of the folded webs underlying the end portions of said flaps, and an adhesive bond between the inner side of the end 30 portion of said flaps and the outer folds of the respective corner webs for securing the box in a permanent set-up position.

SAMUEL REICH.
